UNITED STATES PATENT OFFICE

ROBERT A. LORIG, OF MADISON, WISCONSIN, ASSIGNOR TO BURGESS BATTERY COMPANY, OF MADISON, WISCONSIN, A CORPORATION OF WISCONSIN

HAND LAMP

Application filed April 20, 1929. Serial No. 356,827.

This invention relates to improvements in hand lamps and more particularly to improvements in holders for the bulb sockets of hand lamps of the type disclosed and claimed in the Zook Patent No. 1,701,093 granted February 5, 1929.

In the Zook patent there is disclosed a hand lamp in which the bulb is carried by a separable head pivotally mounted on the battery and adapted to be moved from an operative position in which the bulb is electrically connected to the battery to an inoperative position in which the bulb is disconnected from the battery. The holder includes a backing member which serves as a reflector when in operative position and as a closure member for the lamp when in inoperative position.

In my construction, the backing member of the Zook device is provided with a pair of depending cams between which the bulb socket is mounted and which also receives a wire bail on which the holder is pivoted. The bulb socket may be pivoted between these cams (as disclosed and claimed in the copending application of Halvard F. Nvgard, Serial No. 286,620, filed June 19, 1928) and may be arranged so that it will be compressed by the cams when in one position to prevent removal of the bulb from the socket. When the bulb socket is moved to a second position this compression is released and the bulb may be then removed from the socket. In normal operation the bulb and socket are arranged in the first mentioned position with respect to the backing member and are only moved to the second position when a new bulb is to be inserted in the socket. The present invention comprises positive means for retaining the bulb socket in operative position with respect to the holder.

In carrying out my invention I provide a holder or backing member of the general type disclosed in the Zook patent having depending cams which holder is adapted to be received in the cup at the top of the battery and to be pivotally mounted therein to permit it to assume an operative or inoperative position and connect or disconnect the bulb to the battery. The holder may be provided with a bead or rolled edge where the cams join the

body portion. In connection with this holder I provide a split socket having a pair of pivots adapted to be received in openings in the cams. The cams are provided with lugs to compress the socket when the socket is arranged in a position parallel to the backing member. The socket is further provided with outwardly flaring flanges which are adapted to be received in the rolled edges of the backing member and lock the socket in this position so that it will not accidentally swing on its pivot in the bulb holder and interfere with the operation of the lamp. The flanges are so designed that the socket can be swung on its pivot when desired for the removal of an exhausted lamp bulb and the insertion of a new one.

One form of the invention is shown in the accompanying drawings.

Fig. 1 of the drawings illustrates in part 70 sectional elevation the whole of the battery hand lamp with the incandescent bulb or holder in solid lines for the operative position and in dotted lines for the inoperative position;

Fig. 2 is a similar view of the separable head with the socket in full lines for the normal position and in dotted lines to illustrate its position when a bulb is being inserted or removed;

Fig. 3 is a plan view of the separable head with a backing member shown in section;

Fig. 4 is a side elevation of the backing member before the bulb socket is inserted;

Fig. 5 is an end elevation;

Fig. 6 is a detailed, sectional view on line 6-6 of Fig. 4;

Fig. 7 is a plan view of the bulb socket before its insertion in the backing member;

Fig. 8 is a vertical, sectional view of the 90 bulb socket; and

Fig. 9 is a rear elevation thereof.

In the preferred form of my invention, I employ a battery consisting of one or more dry cells 1 and 2 electrically connected as by 95 connector 3. The battery is arranged in a suitable carton 4, which may be of paper, and which projects above the top of the dry cells to form an oval cup. In this cup I place a metallic cup 5, which is electrically con- 100

nected to one of the poles of the battery, preferably by soldering to the negative can as at 6. An opening 7, in the bottom of the metallic cup 5 allows the other pole, preferably the positive 8, to be exposed. The second pole must be insulated from the cup, as by a sheet of insulating paper 9. This sheet of insulating paper may be extended and bent down to form an insulating separating sheet 10 between cells 1 and 2, in which case the cells need not have individual paper wrappers over the zinc cans. A layer of fusible sealing material 11 may rest upon the bottom of carton 4 and the lower ends of cells 1 and 2 may be imbedded therein. The side edges of opening 7 are bent up, as at 12, for a purpose to be explained hereinafter. At the end of the cup opposite to opening 7, wings 13 are formed as by punching in the sides of the cup 5, the purpose of these wings to be explained hereinafter. A small lug 14 is formed on the bottom of the cup at the end removed from opening 7, as by stamping the metal.

An incandescent bulb 15 is mounted, as by screwing, in bulb socket 16 which is shown in detail in Figs. 6, 7, 8 and 9. The socket 16, preferably of sheet metal, is cylindrical in form with one side longitudinally open, as at 17. The sides of the bulb socket are provided with outwardly projecting lugs 18 adapted to form pivots. The edges of opening 17 are provided with upwardly and outwardly flaring flanges 19 by means of which the bulb socket is locked in position in the holder. The side of the socket opposite the opening 17 may be provided with a circular opening 20. Grooves or threads 21, conforming to the pitch of the threads on the base of the bulb 15, are provided in the wall of the socket.

The bulb socket 16 is carried by a holder consisting of a backing member 22 which is fashioned, as by stamping, from a single piece of material, preferably sheet metal, and has two integral cams 23 depending from the sides thereof (see Fig. 4). Each cam 23 contains a raised portion 24 in which a hole 25 is stamped or drilled. Adjacent one side of the raised portion 24 and spaced slightly therefrom is a hole 26. Adjacent the other side of raised portion 24 is an inwardly stamped lug 27 which may be longitudinal as shown, or may be round. Socket 16 is mounted between cams 23 by inserting lugs 21 into holes 26. Socket 16 is thus free to pivot into either of the positions shown in Fig. 2 of the drawings so that its axis is parallel or perpendicular to backing member 22. In normal operation the socket is in the full line position shown in Fig. 2 of the drawings and when in this position it is compressed by lugs 27 sufficiently to make it difficult to turn bulb 15. The compressibility of socket 16 is facilitated by circular opening 20. Lugs 27 exert compression upon the sides of socket 16

slightly to one side of their middle portion. When the lamp is in normal operation it is desirous that the bulb socket be retained in the full line position shown in Fig. 2 of the drawings and flanges 19 are provided for this purpose. As shown, cams 23 are arranged in planes slightly inwardly of the side edges of the backing member as clearly shown in Figs. 3 and 6 of the drawings providing a bead or rolled edge at the junction of the cam and backing member which forms a recess or depression 28 on the inside of the holder. Flanges 19 are flared upwardly and outwardly so that their outer edges are beyond the wall of the socket and are adapted to be received in these recesses at the inner edges of cams 23 as clearly shown in Fig. 3 of the drawings. This securely locks the bulb socket in operative position and prevents it from accidentally assuming the inoperative position shown in dotted lines in Fig. 2 of the drawings. To remove the bulb from the socket, the thumb or finger is wedged between the bulb 15 and the backing member 22 and the socket swung to the dotted line position shown in Fig. 2 of the drawings in which position the bulb can be readily unscrewed from its socket as it is then free from the pressure exerted by lugs 27.

Looped spring 31, preferably of wire, is bailed to cams 23 by inserting the ends of the spring in holes 25. Raised portions 24 of the cams allow the stub ends of spring 31 to move from one position to another without interfering with socket 16. The holder pivots on this bail when it is flipped from the operative position shown in full lines in Fig. 1 of the drawings to the inoperative position shown in dotted lines in Fig. 1 of the drawings and vice versa.

The holder cooperates with the battery having the cup 5 mounted as described by slipping the looped spring wire 31 underneath wings 13 and over lug 14 so that the base of bulb 15 will contact with the terminal 116 of the battery exposed through opening 7 when the head is in the position shown in solid lines in Fig. 1. The pressure of wings 13 insures a good contact between the base of bulb 15 and the exposed pole 8 of the battery. Since the cup is electrically connected to one pole of the battery at 6, electrical connection is made to the screw thread of the lamp through socket 16 which is in contact with the backing member 22 in several places, 120 the member 22, in turn, being in contact with cup 5 at several points. When the holder moves from one position to the other the corners of cams 23 slide on the bottom of cup 5 and pass beyond the opening 7. The turned-up edges 12 prevent the corners of cams 23 from slipping into opening 7. To put the hand lamp in the inoperative position the backing member 22 is flipped forward to the position shown by broken lines 130

in Fig. 1. The looped spring 31, which remains in practically the same position during this operation, by its cooperation with lug 14, prevents the backing member 22 from interfering with the sides of cup 5 which are always in close proximity. The end terminal of bulb 15 is then no longer in contact with exposed pole 8 of the battery, and the bulb is no longer lighted. The looped spring 31 still acts to maintain the holder firmly in position. The corners of cams 23 are so shaped that when the holder is flipped into either position it assumes such position with a snap since the spring pressure is greatest at the intermediate position. This insures against the holders being in any other position than the operative or the inoperative positions and, furthermore, prevents the holder from being readily moved into the operative position to accidentally light the bulb while the hand lamp is being carried in the pocket or elsewhere. When the holder is in the inoperative position, the backing member 22 covers the top of the cup, fitting very closely along the edges of the cup, and forming a closure therefor. Lip 32 projects slightly beyond the end of cup 5 as shown in dotted lines in Fig. 1. The lip 32 thus acts as a stop for the holder when it has reached the proper inoperative position and protects the bulb against injury by shock during the act of flipping the holder into the inoperative position or in the event that the hand lamp is accidentally struck against a rigid object. When in the operative position backing member 22 acts as a reflector and may be polished or plated to enhance its value in that respect.

Repeated operation of the holder exerts a hammering effect upon pole 8 of cell 2 and, when the cells rest upon the bottom of carton 4, the hammering tends to drive cell 2 lower than cell 1 with the result that the end terminal of bulb 15 may soon fail to make contact with pole 8. Layer of sealing material 11 provides a more rigid base for the cells and overcomes the above named objection.

I claim:

1. A separable head for a hand lamp comprising a holder, cams depending from the sides of said holder, a bulb socket pivotally mounted between said cams, and outwardly flaring flanges formed on said socket and adapted to engage said holder to retain said socket in operative position.

2. A separable head for a hand lamp comprising a holder, a socket pivotally mounted therein and adapted to be moved into positions substantially parallel and substantially perpendicular respectively to said holder, and outwardly flaring flanges formed on said socket and adapted to engage said holder to retain said socket in said parallel position.

3. A separable head for a hand lamp comprising a holder, a socket pivotally mounted

therein and adapted to be moved into positions substantially parallel and substantially perpendicular respectively to said holder, and projections carried by said socket and adapted to engage said holder when said socket is in said parallel position to prevent movement of said socket on its pivot.

4. A separable head for a hand lamp comprising a holder, cams depending from the sides of said holder, the junction of said cams and the body of said holder forming a bead, a bulb socket pivotally mounted between said cams, and outwardly flaring flanges carried by said socket and adapted to be received in said beads to retain said bulb socket in operative position.

In testimony whereof I affix my signature.

ROBERT A. LORIG.
